CLAIM

The ornamental design for a car body, as shown and described.

DESCRIPTION

FIG. 1 is a front perspective view of a car body showing my new design;

FIG. 2 is a rear perspective view thereof;

FIG. 3 is a front view thereof;

FIG. 4 is a rear view thereof;

FIG. 5 is a right view thereof;

FIG. 6 is a left view thereof; and,

FIG. 7 is a top view thereof.

The elements shown in broken lines in the Figures are for environmental purposes only and form no part of the claimed design.
